(57) **CLAIM**

The ornamental design for a plug-in heater, as shown and described.

DESCRIPTION

FIG. 1 is a perspective view of a plug-in heater; FIG. 2 is a front view of the plug-in heater of FIG. 1; FIG. 3 is a right side view of the plug-in heater of FIG. 1; FIG. 4 is a left side view of the plug-in heater of FIG. 1; FIG. 5 is a back view of the plug-in heater of FIG. 1; FIG. 6 is a top view of the plug-in heater of FIG. 1; and, FIG. 7 is a bottom view of the plug-in heater of FIG. 1. The broken lines and the areas within them depict portions of the plug-in heater that form no part of the claimed design.
